UNITED STATES PATENT OFFICE.

AUGUST LEOPOLD LASKA AND FRITZ WEBER, OF OFFENBACH-ON-THE-MAIN, GERMANY, ASSIGNORS TO CORPORATION OF CHEMISCHE FABRIK GRIESHEIM-ELEKTRON, OF FRANKFORT-ON-THE-MAIN, GERMANY.

TRISAZO DYESTUFFS AND PROCESS OF MAKING SAME.

No Drawing. Application filed July 23, 1925, Serial No. 45,695, and in Germany November 15, 1924.

Our invention relates to new trisazo-dye-stuffs probably of the general formula:

15 The new dyestuffs are, when dry, bluish black bodies, soluble in water to a deep dark solution, yielding upon reduction with stannous chloride an arylamin, the 1-hydroxy-2. 20 7.8-triaminonaphthalene-3,6-disulfonic acid, a para diamin base and a triaminonaphthalene, dyeing cotton and wool in bluish black shades and therefore especially adapted for dyeing mixed fabrics of cotton 25 and wool.

The dyestuffs, where the diamin base used belongs to the diphenyl series and the naphthylenediamin used is 1.5-naphthylenediamin, are especially valuable.

30 The new dyestuffs may be obtained by combining at first one molecular proportion of the tetrazo compound of a para-diamin base in mineral acid solution with the 1.8-aminonaphthol-3,6-disulfonic acid and then 35 combining the intermediate body, thus formed, in the usual manner with a monodiazoo compound and a heteronuclear alpha-naphthylenediamin, this term including 1.5- and 1.8-naphthylenediamin. As an alternative, the intermediate body may be at first 40 combined with the naphthylenediamin and then with the monodiazoo compound.

Compared with the analogous dyestuffs described in the U. S. Letters Patent No.

45 688,478, dated December 10, 1901, containing meta-diamins of the benzene series as the final component, the new products are distinguished by the difference of shades and by dyeing half-woollen goods in shades 50 of fuller overshine, retaining the beautiful bluish tone and not changing like those to a reddish black under artificial light.

The following example illustrates the invention, the parts being by weight and all temperatures in centigrade degrees.

55

Example.

18.4 parts of benzidin are diazotized in the usual manner with 57 parts of hydrochloric acid of 20° Bé. and 13.8 parts of 60 sodium nitrite. While stirring and cooling, a neutral solution of 34.1 parts of 1.8.3.6-amino-naphtholdisulfonic acid (monosodium-salt) is slowly poured in. When the combination is complete, the intermediate 65 body or product, thus obtained, is combined with a solution of diazo-benzene, prepared from 9.3 parts of anilin, 150 parts of water, 28.5 parts of hydrochloric acid of 20° Bé, 6.9 parts of sodium nitrite and ice, and 70 made alkaline with carbonate of soda. When no more unchanged diazobenzene can be detected, a solution of 16.55 parts of 1.5-naphthylenediamin in 700 parts of water and 24 parts of hydrochloric acid of 20° 75 Bé are poured in. After stirring for about five hours at 10-15° C. the combination is complete. The dyestuff, corresponding probably to the formula:

80 is worked up in the usual manner. It dyes half-woollen goods in bluish black shades 85 of a full overshine.

In the same manner the process may be conducted with tetrazo compounds of other para-diamins such as of toluidin, dianisidin or diaminodiphenylamin, instead of diazo-benzene other monodiazoo compounds, such as of toluidins, chloroanilins, anisidins and their homologues may be used, instead of 1.5-naphthylenediamin we may use 1.8-

100

naphthylenediamin. All these dyestuffs yield upon half-woollen goods bluish black shades of a full overshine.

Now what we claim and desire to secure by Letters Patent is the following:

1. As new compounds trisazo dyestuffs having probably the general formula:

which are, when dry, bluish black bodies, soluble in water to a deep dark solution, yielding upon reduction with stannous chloride an arylamin, the 1-hydroxy-2.7.8-triaminonaphthalene-3.6-disulfonic acid, a para-diamin base and a triaminonaphthalene, dyeing cotton and wool in bluish black shades and therefore especially adapted for dyeing mixed fabrics of cotton and wool.

2. A process of making trisazo dyestuffs consisting in combining at first one molecular proportion of a tetrazo compound in mineral acid solution with the 1.8-aminonaphthol-3.6-disulfonic acid and then combining the intermediate product, thus formed, with a monodiazot compound and a heteronuclear alpha-naphthylenediamin.

3. As new compounds trisazo dyestuffs having probably the general formula:

which are, when dry, bluish black bodies, soluble in water to a deep dark solution, yielding upon reduction with stannous chlo-

ride an arylamin, the 1-hydroxy-2.7.8-triaminonaphthalene-3.6-disulfonic acid, a para-para 1 diaryldiamin-and a triaminonaphthalene, dyeing cotton and wool in bluish black shades and therefore especially adapted for dyeing mixed fabrics of cotton and wool.

4. A process of making trisazo dyestuffs consisting in combining at first one molecular proportion of a tetrazo compound of the diphenyl series in mineral acid solution with the 1.8-aminonaphthol-3.6-disulfonic acid and then combining the intermediate product, thus formed, with a monodiazot compound and 1.5-naphthylenediamin.

5. As a new compound a trisazo dyestuff having probably the formula:

which is, when dry, a bluish black body soluble in water to a deep dark solution, yielding upon reduction with stannous chloride, anilin, the 1-hydroxy-2.7.8-triaminonaphthalene-3.6-disulfonic acid, benzidin and a triaminonaphthalene, dyeing cotton and wool in bluish black shades and therefore especially adapted for dyeing mixed fabrics of cotton and wool.

6. A process of making a trisazo dyestuff consisting in combining at first one molecular proportion of tetrazotized benzidin in mineral acid solution with the 1.8-aminonaphthol-3.6-disulfonic acid and then combining the intermediate product, thus formed, with diazobenzene and 1.5-naphthylenediamin.

In testimony, that we claim the foregoing as our invention, we have signed our names, this 7th day of July 1925.

AUGUST LEOPOLD LASKA.
FRITZ WEBER.
